UNITED STATES PATENT OFFICE.

BENJAMIN S. SEAMAN, OF CANTON, OHIO.

BICYCLE-SADDLE.

SPECIFICATION forming part of Letters Patent No. 606,393, dated June 28, 1898.

Application filed March 26, 1897. Serial No. 629,334. (No model.)

To all whom it may concern:

Be it known that I, BENJAMIN S. SEAMAN, a citizen of the United States, and a resident of Canton, county of Stark, State of Ohio, have invented a new and useful Improvement 5 in Bicycle-Saddles, of which the following is a full, clear, and exact description, reference being had to the accompanying drawings, making part of this specification.

10 My invention relates to bicycle-saddles; and it consists in a support for a bicycle-seat constructed of a single piece of wood so shaped as to form a cap in the center thereof, the ends of which being bent around and forward 15 to form a pommel held in engagement by the downwardly-curved prongs of a T-head bolt passing therethrough and adapted to engage the spring-support, as hereinafter fully described and claimed.

20 In the drawings, Figure 1 is a perspective view of the saddle. Fig. 2 is a perspective view of the pelvis-pads. Fig. 3 is a perspective view of the support with a portion of the rawhide covering cut away. Fig. 4 is a detail perspective view of the wooden support. Fig. 5 is a cross-sectional view of the saddle.

In the drawings, A represents the frame of the saddle, which consists of a single piece of wood so shaped as to form the cantle, the ends 30 of which are bent around forward and bolted together, forming the pommel. Through the forward end thereof there is inserted a T-head bolt, the free ends or prongs of the head of which are curved downwardly to embrace the ends of the frame-piece, holding them 35 securely together and forming the pommel, through which the bolt passes and engages the spring-support that is held to the seat-posts H by the clamp K. Over the pommel and covering the T-head bolt H' there is placed a pad of soft felt C, as shown in Fig. 2. There is then placed over and stretched upon the frame in a moist condition a piece of rawhide D, the edges thereof being tacked

down to the sides of the support A. This 45 rawhide being placed upon the frame in a moist condition and properly stretched, when dried forms a practically solid support and yet is of sufficient elasticity to yield under pressure. Upon the rawhide support and 50 upon either side thereof are placed heavy felt pelvis-pads E E', and over the entire saddle is placed a leather covering F, which has previously been stamped to conform to the parts of the saddle, the edges thereof being tacked 55 to the upper part of the bicycle-seat support A. For the purpose of retaining the pads in their position and spacing them apart, so as to leave a ventilation-channel in the middle of the saddle, two rows of stitching are provided 60 through the leather covering F and the rawhide support D, as is shown in Fig. 5.

By means of this construction a bicycle-saddle seat is produced having a soft cushioned pommel, and at the same time a practically rigid padded bicycle-seat is provided having a sufficient elastic support which prevents the matting or otherwise crushing out of shape the pads.

Having thus described my invention, what 70 I claim, and desire to secure by Letters Patent, is—

A support for a bicycle-seat consisting of a single piece of wood so shaped as to form a cap in the center thereof, the ends thereof 75 being bent around and forward, forming a pommel, and held in engagement by the downwardly-curved prongs of a T-headed bolt passing therethrough, and adapted to engage the spring-support, substantially as described 80 for the purpose set forth.

In testimony whereof I have hereunto set my hand this 23d day of March, A. D. 1897.

BENJAMIN S. SEAMAN.
